WINDOW ASSEMBLY

Joseph Sylvan, Berkley, Mich.

Application May 14, 1949, Serial No. 93,385

6 Claims. (Cl. 160—90)

1

This invention relates to improvements in window assemblies. It is illustrated in a door structure provided with a window and screen assembly. It is adaptable for use in any suitable window assembly whether the same is embodied in a door or in a window frame designed for stationary placement in the wall of a building.

The invention relates particularly to a window assembly which includes a window frame provided with a pair of window sashes and a screen capable for use in substitution for either window sash and wherein the screen or window sash, whichever is not in use, may be conveniently stored alongside of or overlying the other window sash which is in use, and wherein the construction is such that placement for use or removal or storage may be quickly and conveniently made. The invention is embodied in a construction consisting of a window frame and sash formed of sheet metal and is particularly designed for this type of material. The embodiment of the invention occupies a minimum amount of space and the cost is moderate. Novel means is provided for storing the sash not in use; novel means for facilitating the insertion and removal of a sash is provided; and a novel meeting rail construction for the sash adapted to present a weather-tight seal and retain the sash in position and for facilitating insertion and removal of the sash is provided.

An object is to provide a window assembly of the type described comprising a window frame formed of sheet metal which can be readily secured to supporting window or door frame structure and which has associated therewith upper and lower window sash and a screen sash also formed of sheet metal capable of substitution for either the upper or lower window sash and for storage within the boundaries of the assembly.

Another object is the provision of an assembly of the character described wherein one of the window sash, as for example the lower window sash, is mounted within the frame in the usual window runway and the cooperating sash, such as the upper sash, is held in place by means which provides a weathertight seal, but also permits quick removal of the sash and insertion of a substitute sash in position therefor. The means for holding the readily removable sash in place and for facilitating its replacement is simple and inexpensive and also permits convenient displacement of the sash to a ventilator position.

Another object is the provision of an assembly of the kind described of a storage space for the sash not in use disposed within the boundaries of

2

the assembly and wherein the stored sash is protected.

The construction is also of such a character that the sash elements may be placed within the frame structure for shipment and will occupy a minimum amount of space.

Other objects, advantages and important features will more fully appear from the following description, claims, and accompanying drawings, wherein:

Fig. 1 is an elevation of a door structure embodying my window frame assembly;

Fig. 2 is a perspective of a fragment of the structure shown in Fig. 1 taken along a section line through the meeting rails of superposed sash;

Fig. 3 is a vertical sectional view partly broken away taken along a line 3—3 of Fig. 1;

Fig. 4 is a horizontal sectional view partly broken away taken on the line 4—4 of Fig. 1;

Fig. 5 is a horizontal sectional view partly broken away taken on the line 5—5 of Fig. 1;

Fig. 6 is a horizontal sectional view partly broken away through the upper portion of a window assembly such as Fig. 1 showing the upper window sash displaced for ventilation;

Fig. 7 is an elevation similar to that of Fig. 1 showing a modified construction;

Fig. 8 is a sectional view taken on a line such as 8—8 of Fig. 7 showing disposition of the sash within the frame for shipment and with an additional screen sash assembled therewith; and

Fig. 9 is a sectional view taken on the same line as Fig. 3 through a construction such as Fig. 1 showing the screen sash in superposition above the lower window sash and the upper window sash stored.

I have illustrated the invention as embodied in a door of the general character disclosed in my co-pending application, Serial No. 9,691, filed February 20, 1948 and which was patented on January 15, 1952, as Patent No. 2,582,467, though differing in detail from the construction of such application. Such application shows a metal clad door and such is the type here shown. The door includes the foundation structure or a window frame assembly. This window frame assembly includes a pair of cooperating frame side rails 20 which may be formed of wood and covered on opposite sides by metal sheets 22. There is a header portion for the frame also shown as formed of wood indicated as 24. This wood frame portion is covered by metal sheets 26. There is a sill frame portion 28 covered by metal sheets 30.

The above construction forms merely the environment for my improved window frame assembly. The window frame assembly itself consists of a pair of upright side frame members 32 shown particularly in Figs. 1, 2, 4 and 5. Each side frame member is formed of sheet metal shaped to define a channel portion the side walls of which are folded over as shown in Figs. 4 and 5, and which channel portion is adapted to seat over the metal sheathed upright members 28 as shown in Figs. 2, 4 and 5. Each of these frame members 32 is so shaped as to define a flange 34 which constitutes one side wall of a window guideway and against which the window sash rests. The header member 36 of my window assembly is shown particularly in Fig. 3 and it is formed of sheet metal and exhibits a channel portion which is adapted to be received over the metal sheathed header 24. One of its side walls is doubled over on itself and extended inwardly to form one side wall 38 of an upwardly opened window sash receiving header channel. The other side wall of this upwardly opened window sash receiving header channel is formed by an angular member 40. One angular portion of this member 40 indicated as 42 is received underneath a part of the side wall 38 as shown in Fig. 3.

The sill portion of the frame is formed of sheet metal shaped to define a downwardly open channel 44 as shown in Fig. 3 which channel is adapted to be received over the metal sheathed sill member 28. One side wall of this channel 44 is folded back upon itself as at 46 and over the bottom of the channel and then upwardly forming a lip 48 which constitutes an inner side wall against which the lower window sash rests as shown in Fig. 3. This window sash is held against this inner side wall 48 by the side walls 34 of the vertical rails of the frame heretofore described.

There is mounted within this frame assembly a lower window sash 50 and an upper window sash 52 and a screen 54. Each window pane is bounded by metal sash as shown. The meeting rails of the metal sash are peculiarly formed to insure interengagement of the two window sashes as shown in Figs. 2, 3 and 8. The header rail of the lower window sash is indicated as 56. It has one side wall folded back upon itself forming an upwardly projecting ledge or flange 58. This flange is adapted to normally lie flat against its side wall. The opposite side wall is folded over upon itself forming a relatively narrow flange 60 spaced from such side wall as shown in Figs. 2 and 3. This flange 60 is adapted to serve the purpose of a hand grip member and also serves as shown in Fig. 3 to exert a pressure against a stored screen to hold the parts against rattle.

The meeting rail of the upper sash is formed of sheet metal and is shown as engaging the lower margin of the glass pane. One side wall of its channel 62 is folded over upon itself as at 64 forming a flange that normally lies flat against such side wall, but this flange is adapted to be swung resiliently outwardly as shown in Figs. 2 and 3 so as to receive thereunderneath the flange 58 of the meeting rail of the lower sash. This forms a weathertight joint. It also interlocks the sash together along their meeting rails so as to assist in retaining the upper sash in position. The opposite side wall of this channel 62 is folded outwardly upon itself forming a relatively narrow flange 66 spaced from the side wall and adapted to serve as a handle as shown in Figs. 2 and 3. The upper and lower sash each bear against the

guide wall 34 of the side rails of the frame. This is true as to the door structure shown in Figs. 1 through 6 and the window structure shown in Figs. 7 through 8. These two structures are substantially the same except for slight variations to suit window and door conditions hereinafter specifically referred to.

The lower edge of the lower window sash is provided with a channel shaped sill member 68. One side wall of this sill member is folded over upon itself as at 70 as shown in Fig. 3 to overhang the upright ledge 48 of the sill portion of the frame and to also form a hand lift portion.

The upper margin of the upper sash is provided with a header section formed of sheet metal and indicated as 72 which is channel shaped and seats over the upper margin of the glass pane. One side wall of this channel shaped member is folded over upon itself as at 74, as shown particularly in Fig. 3. When the two sash are disposed in superposed relationship as shown in Fig. 3, the header section of the upper sash does not extend to the top of the channel in the header of the frame. It is noted that there is a space in Fig. 3 above the top of the upper sash within the header channel of the frame and this upper sash may be lifted within this space, the flange 74 passing over the lip 38. This permitted elevation of the upper sash is sufficient to disengage the meeting rails of the upper and lower sash.

The lower sash is held in place against the side wall element 34 of the upright rails of the frame by one side wall of a channel member 76. This channel member is shown particularly in Figs. 1, 2 and 5. It may be secured in place by nails 78 driven through its bottom portion and into the wood side rails 20 of the foundation of the frame as shown in Fig. 5. This channel member is shown as of a shorter length than the vertical height of the lower window sash. Its inner side wall forms together with the side wall 34 a guideway for the lower window sash. This inner side wall is bent inwardly and folded over as at 80 so as to define a relatively narrow guideway within which the screen 54 may be stored as shown in Fig. 5.

The upper sash is held against the side wall 34 when its meeting rail is engaged with the meeting rail of the lower sash as shown in Fig. 3 by virtue of such engagement and also by virtue of the fact that its header is received within the header channel of the frame as shown in Fig. 3 and as previously described, but it is also held against such side wall 34 by rotatable retaining elements 84. These retaining elements are in the form of pins as shown particularly in Figs. 2 and 4 extending through the upright frame members and into the wood side rails 20. The outer ends of these pins are bent over as at 86 so that in the position shown in Fig. 4 these outer ends bear resiliently against the upper sash holding it against the guide wall 34. It is apparent that when these pins 84 are rotated through an arc in excess of 90° (note Fig. 6), the upper window sash may be moved laterally within the frame and such movement is sufficient to permit disengagement of the meeting rails of the two sash providing the upper sash is lifted to accomplish such disengagement.

The screen is illustrated as provided with a metal frame extending thereabout. The metal frame which extends about the screen is formed along one edge shown as the sill portion in Figs. 3 and 9 to correspond with the formation of the 75 sill portion of the upper window shown in Fig.

3. This portion of the screen frame has a flange section 88 which projects below the edge of the screen frame proper. As shown in Fig. 1, this sill member has a length less than the width of the screen so that it will not interfere with movement of the screen into the guide channel 76. Its width is such, however, that when the screen is seated upon top of the lower window sash as shown in Fig. 9, the two meeting rails are interengaged. When the screen is in storage as shown in Fig. 3, this flange portion engages the sill of the window frame assembly.

The arrangement is such that when the two window sashes are superposed as shown in Fig. 3, the screen may be stored within the channels 76 as shown in such figure. The projecting flange 60 of the head of the lower window sash is shown bearing against the screen sash to assist in holding it snugly in place. The inturned portions 80 of channel 76 form with the opposite side wall of the channel a narrow guide within which the relatively thin screen frame is supported. When it is desired to install the screen in the upper portion of the window opening above the lower window sash, the screen may be removed from its stored position. The retaining pins 84 will then be rotated to permit the upper window sash to be moved laterally after having been lifted. It can be moved laterally to completely disengage its meeting rail from the meeting rail of the lower sash and then lowered into the channels 76 for storage. The screen can then be placed in the upper portion of the window opening above the lower window sash and its meeting rail engaged with the meeting rail of the lower sash as shown in Fig. 9.

The stationary window construction shown in Figs. 7 through 9 is substantially the same as the door window construction shown in the first six figures of the drawing except that the screen storage channels 76 are mounted in the upper portion of the window opening and the rotatable retaining elements 84 are mounted in the lower portion of the window opening. This is an alternative arrangement as that shown and described heretofore. Either form may be used. Fig. 8, however, shows the wood sill of the stationary window frame as having a outer metal strip of angular shape identified as 90 secured thereto and overlapping the outer wood sill 92 of a conventional window frame.

If it is desired to provide a limited amount of ventilation without inserting a screen above the lower window sash, this may be accomplished by moving the upper window sash to the position shown in Fig. 6. It is apparent how this can be done. This will provide a limited opening and the upper window sash is supported upon the flange 60 of the header portion of the lower window sash between said sash and the upper margin of the screen and it rests against the window retainers 84. In Figs. 7, 8 and 9 the frame provides a storage space for the screen at the top instead of at the bottom. The construction is otherwise as heretofore described in Figs. 1 to 6. The screen is shown as stored at the top in Fig. 8. The screen is of light weight and the walls of the channel 76 grippingly engage the screen so as to hold it elevated. When so stored it is inverted and the sill portion in Fig. 3 is shown at the top in Fig. 8.

The construction is such that a weathertight seal is formed and the windows cannot be opened from the outside.

Fig. 8 shows one means whereby a window as-

sembly could be arranged for shipment and an additional screen shipped with the assembly hereinabove described. The additional screen is indicated as 96. It would lie substantially within the boundary of the assembly frame.

What I claim is:

1. In a window sash carrying frame having a pair of side rails, a bottom rail and a top rail, said side rails provided with opposed complementary outer guide walls for the sash, a pair of sashes disposed in superposed relationship within the frame bearing against said guide walls, each side rail of the frame provided adjacent one end of the frame with a sash guide channel having a wall spaced laterally inwardly from said guide wall forming therewith a second window channel for one of said sash, said first mentioned guide channel having walls of a height not greater than the window sash for which it forms with the outer guide wall the second mentioned channel, a window sash retaining element rotatably mounted upon each side rail of the frame intermediate the end of said first mentioned guide channel and the adjacent end of the frame, said window sash retaining element having a part adapted upon rotation of the element to one position to be substantially in line with the inner window sash engaging face of the second mentioned channel and adapted in another position of rotation to be offset inwardly and out of line with the inner window sash engaging face of the second mentioned channel.

2. In a window sash carrying frame having a pair of side rails, a bottom rail and a top rail provided with a header channel, said side rails provided with opposed complementary outer guide walls for the sash, a pair of sash disposed in superposed relationship within the frame bearing against said outer guide walls, said sash having meeting rails formed for interengagement and having a combined height somewhat less than the vertical distance between the bottom rail of the frame and the bottom of the header channel, each side rail of the frame provided with a sash guide channel having a wall spaced laterally inwardly from said guide wall forming therewith a second channel for one of said sash, the walls of said first channel having a height not greater than the height of one sash, a window retaining element rotatably mounted upon each side rail of the frame spaced between said first sash guide channel and the adjacent end of the frame, said element having a part offset laterally from its axis of rotation and adapted in one position of rotation of the element to bear against a sash disposed opposite the element and against said outer guide wall of the frame and adapted in another position of rotation of the element to be swung away from said sash.

3. In a window sash carrying frame having a pair of side rails, a bottom rail and a top rail, said side rails provided with opposed complementary outer guide walls for the sash, a pair of sashes disposed within the frame in superposed relationship bearing against said outer guide walls, said sashes having their meeting rails formed for interengagement when the windows are superimposed, window guide channels secured in opposed relation to the side rails of the frame at one end of the frame and spaced from the outer guide walls of the frame forming with said outer guide walls a guideway for a sash, said guide channels themselves forming opposed guide channels for a sash, said guide channels having a height less than the height of a single sash, said side rails of the frame provided

with complementary sash retaining elements, one element rotatably mounted upon each side rail, said elements spaced vertically but substantially in line with the inner walls of said guide channels, each of said elements being rotatably swingable to a position substantially in line with the outer wall of its guide channel.

4. In a sash carrying frame having a pair of side rails, a bottom rail and a top rail, said side rails provided with opposed complementary outer guide walls for a sash, a pair of sash disposed within the frame in superposed relationship bearing against said outer guide walls and with the meeting rails of the two windows in abutting relationship, said meeting rails formed for inter-engagement, a sash guide channel secured to each said rail of the frame at one end and spaced from the outer guide wall of the frame forming therewith a guideway for one of the sash and itself adapted to receive another sash, said guide channels disposed in opposed complementary relationship and having a height not greater than a single sash, a pair of window retaining elements one rotatably mounted upon each side rail of the frame, said elements spaced vertically from but substantially in line with said guide channels, said elements rotatable into engagement with the adjacent sash to hold it against the outer guide walls or rotatable out of engagement therewith to permit movement laterally of the sash away from said outer guide walls.

5. The invention defined in claim numbered 4 characterized in that each of said first mentioned sash guide channels comprise a generally rectangular channel member having opposed side

walls, one of said walls adapted to abut the side rails of the frame, the wall opposite said one wall having an edge portion spaced from its adjacent wall and defining therebetween a sash receiving opening.

6. The invention defined in claim numbered 4 characterized in that each of said first mentioned sash guide channels comprise a generally rectangular resilient channel member having opposed side walls, one of said walls adapted to abut the side rails of the frame, the wall opposite the said one wall having a free edge portion spaced from its adjacent wall and forming therebetween a sash receiving channel opening, and the walls of said channel tensioned toward each other to grip a sash disposed therein.

JOSEPH SYLVAN.
